EDWIN H. FOREMAN, OF NEW YORK, N. Y.

SWIMMING GARMENT

Application filed July 12, 1929. Serial No. 377,635.

This invention relates to a swimming garment especially designed for use by women.

The principal object of the invention is to provide a swimming garment so cut that the back and sides of the bust of the wearer will have uninterrupted exposure from the shoulders to a point adjacent the waistline of the wearer, and yet which is so formed that the breasts of the wearer will remain covered by the front of the garment irrespective of the position which the wearer of the garment assumes.

In the drawings:

Figure 1 is a view looking at one side and part of the front of the garment; and

Figure 2 is a view looking at the back of the garment.

In its preferred form, the garment is knitted, the back being knitted as one piece and the front as another, which back and front are sewed together along lines 1 and 2. The back opening is cut out, as at 3, and the side openings, as at 4, so that in effect two straps 5 extend from the body of the back over the shoulders of the wearer to the front of the garment. The extent to which the side and back openings are cut in the downward direction is governed by the desire of the maker, since the garment is so constructed, as will hereinafter appear, that the front of the garment being provided with breast receiving pockets formed by the darts 6 will closely fit the body of the wearer and completely cover the breasts, in such manner that no matter what the position of the wearer may be the sides of the breasts will not be exposed.

It has been the practice in an attempt to get these low-cut garments to cut an arm-hole in each side of the garment and then a lower opening, so that in effect side straps extend under the arm from the front of the back to the opening and thus maintain the front of the garment in position so that it will effectively cover the breasts of the wearer. However, the disadvantage in this is that the wearer does not have absolute freedom of movement and also the maximum body surface is not exposed to the sun.

In the present garment, the front portion is provided with breast receiving pockets which

closely fit the outer sides of the breasts and thus prevent them from becoming exposed at the side openings of the garment.

In the illustrated form, each of these pockets is formed by making the distance from the top of the shoulder, along the front edge of the side opening to the bottom thereof, less than the distance from the same point on the shoulder to a point in the horizontal line of the bottom of the side opening along a line which passes over the breast.

This effect is produced preferably by cutting a dart 6 inwardly from the front of the side opening toward the front center line of the garment and drawing the edges of the thus cut dart together and securing them, although, of course, it must be understood that this effect which has been described above may be produced other than by the use of a dart.

The result of this construction is that the front of the garment is provided with breast receiving pockets and the front edge of each side opening snugly fits the body of the wearer, and the breasts are retained within the pockets and consequently prevented from being exposed through the side openings of the garment, even though these openings be extensive both vertically and horizontally and even though the back be extensive and only separated from the side openings by what in effect are straps.

The inherent tension of the knitted garment effectively retains the garment in the condition which has been described above, and it is due to this that the maximum exposure of the sides and back of the bust of the wearer may be attained, with nevertheless the covering of the breasts at all times.

I claim:

1. A knitted form-fitting swimming garment having arm openings extending substantially below the armpits of the wearer, the forward portion adjacent the arm openings below the breast portion being made shorter than the more central portions of the garment so as to provide tension at the said forward portion, causing the garment adjacent the arm openings to lie close to the body.
2. A knitted form-fitting swimming gar-

ment having arm openings extending substantially below the armpits of the wearer and a low-cut back opening, means for making the front of the arm openings shorter than the more central portions of the garment, said means comprising dart portions extending inwardly below the breast portion toward the center line of the garment, thus shortening the normal length of the forward edges, causing the garment adjacent the arm openings to lie close to the body.

3. A woman's knitted form-fitting swimming garment having large arm openings tapering downwardly to a point in proximity to the waist line, a low cut back opening also extending downwardly to a point in proximity to the waist line, the forward portions adjacent the arm openings being shortened above the waist and below the breast portion so as to provide tension at the said forward portions, causing the garment adjacent the arm openings to lie close to the body.

In testimony whereof, I have signed my name to this specification this 3rd day of July, 1929.

EDWIN H. FOREMAN.
